Inventor: James O'Dowd.

By Harriet Payward Attorney.

UNITED STATES PATENT OFFICE.

JAMES O'DOWD, OF TAPANUI, NEW ZEALAND.

ROOF-GUTTER.

No. 846,238.

Specification of Letters Patent.

Patented March 5, 1907.

Application filed August 28, 1905. Serial No. 276,038.

To all whom it may concern:

Be it known that I, JAMES O'DOWD, a subject of His Majesty the King of Great Britain and Ireland, residing at Tapanui, in the Provincial District of Otago, in the Colony of New Zealand, have invented certain new and useful Improvements Relating to Roof-Gutters, of which the following is a specification.

This invention relates to gutters of roofs, and provides an improved cover for said gutters, whereby dust and dirt are excluded and birds are prevented from building under the roof. The cover also acts as a stay or support for the gutter.

According hereto lengths of plain galvanized iron each having a flange upon its outer edge to fit over the molded edge of the guttering are nailed upon the roof in such manner that their flanged edges may be sprung over the molded edge of the guttering to hold it securely in position.

Referring to the accompanying drawing, Figure 1 is a sectional elevation, and Fig. 2 a front elevation, showing the invention.

The lengths 1 of plain galvanized iron have a flange 2 upon their outer edge adapted to fit over the molded edge 3 of the guttering 4. The lengths of iron 1 rest upon the convexities of the corrugated iron 5 composing the

roof, to the woodwork of which they are secured by nails 6, one of which is shown in the Figs. 1 and 2. Rain-water runs down the depressions of the corrugated iron 5 and through the spaces between the lengths of iron 1 and the said depressions and into the guttering 4.

The lengths 1 are adjusted in position by passing the flange 2 upon the molded edge 3 and then securing the lengths by the nails 6. The said flange 2 has its edge stiffened by wire 7.

What I do claim, and desire to secure by Letters Patent of the United States, is—

For the purpose indicated, in combination with a corrugated-metal roof lengths of plain galvanized iron having one edge resting upon the convexities of the corrugated iron and the other edge flanged to fit upon the molded edge of the guttering, and means for securing the lengths of iron to the roof, substantially as set forth herein.

In testimony whereof I have signed my name to this specification in the presence of two witnesses.

JAMES O'DOWD.
